UNITED STATES PATENT OFFICE.

FRANCIS S. KINNEY, OF PEQUANAC, NEW JERSEY, AND WILLIAM H. BUTLER, OF BROOKLYN, NEW YORK, ASSIGNORS TO THE KINNEY TOBACCO COMPANY, OF NEW YORK, N. Y.

CIGARETTE-BOX.

SPECIFICATION forming part of Letters Patent No. 369,063, dated August 30, 1887.

Application filed May 12, 1887. Serial No. 237,935. (No model.)

To all whom it may concern:

Be it known that we, FRANCIS S. KINNEY and WILLIAM H. BUTLER, citizens of the United States, residing at Pequanac, Morris county, New Jersey, and Brooklyn, Kings county, New York, respectively, have invented certain new and useful Improvements in Cigarette-Boxes, fully described and represented in the following specification and the accompanying drawings, forming a part of the same.

This invention relates to a box or package which is especially designed for use in putting up cigarettes for the retail trade, it being the object of the invention to provide a package for this purpose which will serve as a convenient pocket-receptacle for the cigarettes until the lot contained in the package is used.

The invention relates particularly to a means for preventing the cigarettes from moving from their proper places in the box after a part of the lot has been used.

In order to give a full understanding of the invention, it will now be described in detail, reference being had to the accompanying drawings, in which—

Figure 1 is a plan view of a cigarette box or package constructed according to the present invention, the cover of the box being removed, so as to expose the contents. Fig. 2 is a similar view showing a portion of the contents removed. Fig. 3 is a cross-section taken on the line *x* *x* of Fig. 1, showing the cover applied to the box. Fig. 4 is a similar view showing a part of the contents removed; and Figs. 5, 6, 7 are similar views illustrating slight modifications, which will hereinafter be explained.

Referring to said figures, it is to be understood that the box *A* is of rectangular form and of sufficient depth to hold two or more rows or layers of the cigarettes, *a*. The upper edges of the side of the box are cut away, as indicated at *b*, to expose the ends of the cigarettes. The corners of the box are, however, left of full height, so as to afford support for the cover and prevent it from pressing too heavily upon the cigarettes. This feature, however, forms no part of the invention, it being claimed in a separate application filed by Francis S. Kinney and now pending in the Patent Office.

The cover *B* is of substantially the same form as the box-body, but is slightly larger, so as to fit over the body in the usual manner, as illustrated in Figs. 3 to 6.

With the box constructed as thus far described there is no means, after a portion of the cigarettes have been removed, for preventing those remaining in the box from shifting their position, so as to rattle about the box and thus shake the tobacco out of the wrappers, and this, when the box is carried in the pocket of the user, is a serious objection, as the last of the cigarettes of a box are liable to become damaged. To avoid this difficulty we provide the box with a retaining-strip, *C*, which extends the length of the box between the rows of cigarettes, and is provided with an upward projection, *c*, which passes between two of the cigarettes of the upper layer, so as to rest against the inside of the cover. By this means the bottom row of cigarettes will be retained in position until the top row is entirely removed, as indicated in Figs. 4 to 6, and by means of the upward projection *c* the cigarettes of the top row are prevented from moving but very little, even after a portion of them have been removed.

The retaining-strip *C* may be made in a variety of ways, the preferred construction being that shown in Figs. 1 to 4, in which the strip is shown as composed of a plain piece of card-board or pasteboard bent at its middle, so as to form the projection *c*, and of a length to just fit easily into the box-body, so that after the upper row of cigarettes is used the strip can readily be removed and replaced as it is desired to remove the cigarettes of the lower row. The retaining-strip may, however, be modified in its form without departing from the essential feature of the invention. For example, it may, if preferred, be provided with downwardly-turned ends *d*, as shown in Fig. 5, which will cause it to fit more snugly into the box-body; or the projection *c*, instead of being formed by bending the strip, as shown in Figs. 1 to 5, may be formed of a lip cut out of the strip and turned up at right angles, as shown in Fig. 6.

In some cases it may be desired that the retaining-strip should be attached to the box-

body, and this can readily be done by making the strip in two parts and cementing the downwardly-turned ends to the sides of the box-body, as shown in Fig. 7. In this case, instead of removing the retaining-strip to gain access to the lower row of cigarettes, the strip will be turned up, as also shown in said figure.

Other modifications may be made in the form and arrangement of the retaining-strip without departing from the essential feature of the invention or losing its advantages; but those shown are deemed sufficient, as they fully illustrate the invention and the manner of applying the same.

15 We are aware of the constructions described in the United States Letters Patent Nos. 165,233, 315,454, and 194,914, and we do not claim anything therein shown; but

What we do claim is—

The herein-described cigarette-box, consisting of the box-body and its cover and the retaining-strip C, of less width than the box, but extending the length of the box between two rows or layers of cigarettes, so as to bear against and hold both rows in place, and having the upward projection c, which passes between two of the cigarettes of the upper row and rests against the cover, substantially as described, and for the purposes set forth.

In testimony whereof we have hereunto set our hands in the presence of two subscribing witnesses.

FRANCIS S. KINNEY.
WM. H. BUTLER.
